 Square D Company, Detroit, Mich., a corpora-
 tion of Michigan

Application July 25, 1941, Serial No. 403,936

7 Claims. (CL 200—88)

This invention relates to automatic electric circuit breakers and more particularly to the current responsive tripping means for effecting the automatic opening of such circuit breakers upon current overload.

One object of the present invention is to provide a simple and economical but effective combined thermal and magnetic tripping means for an automatic electric circuit breaker.

Another object of this invention is to provide tripping means for an automatic electric circuit breaker including a yoke and a movable armature member with an intermediate member carrying a latching surface moved by the armature to effect tripping of the circuit breaker.

Another object of the invention is to provide a combined thermal magnetic tripping means for a circuit breaker according to the preceding object in which a bimetallic member is provided for also effecting movement of the intermediate member carrying the latching surface.

Other objects and features of the invention will be readily apparent to those skilled in the art from the specification and appended drawings illustrating certain preferred embodiments in which:

Figure 1 is a vertical sectional view of a form of circuit breaker including the current responsive tripping means of the present invention.

Figure 2 is a detail plan view of the tripping means according to the present invention shown with the circuit breaker cover removed.

Figure 3 is a detail sectional view on the line III—III of Figure 1.

Figure 4 is a detail sectional view on the line IV—IV of Figure 1.

Figure 5 is a partial vertical sectional view showing a slightly modified form of the tripping means.

The present invention has been illustrated in connection with a circuit breaker mechanism which comprises a base 1 having a conducting strap 2 mounted on one end ledge thereof and carrying at its interior end a stationary contact 3, the connector 2 extending through an opening in a fiber plate 4 which closes the end of the base. Exterior of the plate 4 is a terminal connector 5 for attachment of circuit wiring. Guided for rectilinear movement within the base is a generally U-shaped element 6 upon whose long leg is pivotally mounted, by interengaging notches, a contact bar 7 carrying at one end a movable contact 8 cooperating with the stationary contact 3. Fiber plates indicated at 9 combine with the plate 4 to enclose the contacts 3 and 8 within an arcing chamber. An operating handle is provided at 11 pivotally mounted upon a shaft 12 and having a cam surface 13 cooperating with the flat surface of the member 6 to effect manual movement of the contact bar 7. A compression spring 14 is disposed between the bottom of the base 1 and the bar 7 to bias the same.

The lower end of the base is provided with an end facing terminal comprising a conducting connector 15 inserted in slots in the opposite side walls of the base from the front and maintained against endwise removal by both a terminal screw 16 and an adjusting stud 17. A mid-portion of the connector is pressed outwardly at 18 to take up any slack or play in the connector mounting. A tab 19 is pressed out of the connector and the stud 17 is threaded into the tab 19 to provide for adjustment of the free end of a bimetallic member 21 welded on the end of the connector, thus providing for adjustment of the calibration of the breaker. Embracing the bimetallic element 21 is a magnetic yoke 22 which is of generally U-shape provided with side pins 23 received within slots on opposite side walls of the base to mount the yoke. A magnetic armature element 24 is provided having a central slot 25 through which the contact bar passes in its automatic tripping and resetting movements. An intermediate non-magnetic element 26 is provided between the sides of the yoke. This element has return bent tabs at its front end at 27 and the loops thus formed bear against the inside surface of an insulating fiber plate 28 which, with the metal plate 29, is sealably attached to the breaker to form a cover therefor. The member 26 rotates about the engagement of the loop 27 with the inner surface of the fiber sheet 28. The armature 24 has recessed rounded portions 31 received within the loops 27 which form bearings for the rotation of the armature. The upper end of the armature is provided with projecting tongues 32 received within notches in the opposite side walls of the base which serve to limit the movement of the assemblage. Mounted upon the non-magnetic intermediate member 26 is a resilient spring strip 33 welded to the intermediate member adjacent a midpoint and formed to provide a latching tip at 34 biased by its resiliency away from the plane of the intermediate member, but whose position is limited by the engagement with the intermediate member of the flange 35 formed at the end of the leg 36. The opposite end of the spring strip 33 is formed as shown to engage both the surface of the fiber sheet 28

and the armature 24. The engagement with the fiber sheet 28 is indicated at 37 and the engagement with the armature is indicated at 38. By its engagement with the fiber sheet the resiliency of the spring strip biases the intermediate member 26 in a counterclockwise direction as viewed in Figure 1. Similarly, the engagement of the resilient spring strip with the armature 24 at the point 39 biases the armature as well in a counterclockwise direction. The limiting position of the armature is determined by a stationary stop on the base and the limiting position of the intermediate member 26 and hence the position of the latching tip 34 is determined by adjustment of the bimetal 21, the bimetal 21 being provided with the reduced tongue 39 received within a slot 41 in a right angle leg 42 provided at the free end of the intermediate member 26.

The circuit breaker mechanism, as shown in full lines in Figure 1, is in its normally operating closed circuit position. The dotted lines of the mechanism indicate the automatic tripped position in which the circuit through the breaker is open upon the occurrence of an excess current condition. The breaker is reset into latched position by manipulation of the operating handle 11 and the contacts are moved to their manual "on" and "off" positions for normal switching operation also by manipulation of the handle 11, the operation of the mechanism itself being more fully described in my Patent No. 2,096,546 but with the handle operation described in my Patent No. 2,096,545, both issued October 19, 1937.

The operation of the tripping mechanism is as follows:

For low current overloads of continued duration, the bimetal 21 becomes heated by the passage of current therethrough and flexes in a clockwise direction to move the intermediate member 26 and, accordingly, the latching tip 34, to disengage the contact bar 7 which then rotates in a clockwise direction into the dotted line position under the bias of the spring 46. Upon the occurrence of heavier overloads, magnetic elements of the tripping means operate quicker than normal thermal flexing of the bimetal 21 to effect the tripping of the breaker mechanism in a shorter elapsed time than would be taken by the bimetal alone. When the flux induced in the magnetic circuit formed by the armature 24 and yoke 22 becomes sufficient, the armature is rotated in a clockwise direction and strikes the latching tip 34, moving it downwardly to release the bar 7 as before. The movement of the latching tip 34 may be effected independently of movement of the intermediate member 26, or these two members may move together as a unit, depending upon whether the bias of the spring strip 33 or the resistance of the intermediate member to movement is the greater. As a practical matter, the actual tripping movement of the latching tip is probably a combination of these movements. It is seen that with this arrangement the moving armature 24 strikes the latching tip 34 a hammer blow to overcome the initial static friction opposing movement thereof.

While the operation of the tripping means for the breaker has been described in terms of thermal or magnetic effects operating separately, it is, of course, possible that they may have a combined operation where the magnetic force is insufficient to move the latching tip alone; but, combined with the force exerted by the ther-

mal flexing of the bimetal, the two exert a force sufficient to effect eventual release of the contact bar.

In the modified form of the invention illustrated in Figure 5, the leg 38 on the spring strip 33 is elongated sufficiently for the flange 38 to directly engage the lower surface of the bimetal 21. In this arrangement the leg 42 on the intermediate member 46 is omitted, as is the tongue 39 on the bimetal. In this arrangement the magnetic operation is the same as previously described for the preferred embodiment, but in the thermal tripping the force exerted by the bimetal 21 is passed directly to the latching tip 34 through the leg 38 instead of operating on the intermediate member 26. Again, whether the latching tip is moved without moving the intermediate member 26 or the two are moved bodily together will depend upon the value of the bias of the spring 33 and the resistance which the intermediate member offers to rotation, the actual operation being immaterial to the releasing effect which is produced.

While this invention has been described in connection with a particular circuit breaker mechanism to show a complete operative structure, it is understood that the tripping means according to the present invention is not limited to any particular mechanism but may be utilized in many other distinct mechanism forms to which it is adaptable and, while certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In an automatic electric circuit breaker having separable contacts and means releasable to effect separation of said contacts, current responsive means for effecting the release of said releasable means upon the passage of an overload current through the circuit breaker comprising a magnetic yoke, means energizing said yoke in response to the flow of current through the breaker, an armature member movable toward said yoke to effect the release of said releasable means upon the passage of overload current, a non-magnetic intermediate member carrying a latching surface engaging said releasable means and positioned in the path of said movable armature so as to be moved thereby into a position where the releasable means is released, said intermediate member having looped portions at one end with the outside of the loop bearing against a fixed part to provide a bearing for rotation of the auxiliary member and said armature having rounded portions received within the inner portions of the loop and rotating therein for pivotal movement.

2. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke, means energizing said yoke in response to the flow of current through the breaker, an armature member adapted to be attracted to said yoke upon passage of an overload current, an auxiliary member carrying a latching surface en-

gaged by said releasable means, means for effecting movement of said latching surface in response to the flex of said bimetallic member, and means for effecting movement of said latching surface in response to movement of the armature into attracted position, said intermediate member having looped portions at one end with the outside of the loop bearing against a fixed part to provide a bearing for rotation of the auxiliary member and said armature having rounded portions received within the inner portions of the loop and rotating therein for pivotal movement.

3. In an automatic electric circuit breaker having separable contacts and means releasable to effect separation of said contacts, current responsive means for effecting the release of said releasable means upon the passage of an overload current through the circuit breaker comprising a magnetic yoke, means energizing said yoke in response to the flow of current through the breaker, an armature member adapted to be attracted to said yoke upon the occurrence of an overload current, an auxiliary member, a thin metal strip mounted on said auxiliary member and formed to provide a latching surface engaged by said releasable means, said latching surface being constituted by the main flat surface portion of the strip as distinguished from an edge or end thereof, and means providing for movement of said latching surface into releasing position upon movement of the armature into attracted position.

4. In an automatic electric circuit breaker having separable contacts and means releasable to effect separation of said contacts, current responsive means for effecting the release of said releasable means upon the passage of an overload current through the circuit breaker comprising a magnetic yoke, means energizing said yoke in response to the flow of current through the breaker, an armature member adapted to be attracted to said yoke upon the occurrence of an overload current, an auxiliary member, a thin metal strip mounted on said auxiliary member and formed to provide a latching surface engaged by said releasable means, said strip being biased away from the auxiliary member but retained in a definite position by the engagement of an abutment thereon with said member, said strip being positioned to be engaged by said armature in its movement toward attracted position.

5. In an automatic electric circuit breaker having separable contacts and means releasable to effect separation of said contacts, current responsive means for effecting the release of said releasable means upon the passage of an overload current through the circuit breaker comprising a magnetic yoke, means energizing said yoke in response to the flow of current through the breaker, an armature member adapted to be attracted to said yoke upon the occurrence of an overload current, an auxiliary member, a thin metal strip mounted on said auxiliary member and formed to provide a latching surface engaged by said releasable means, said strip being biased away from the auxiliary member but retained in a definite position by the engagement of an abutment thereon with said member, said strip being positioned to be engaged by said armature in its movement toward attracted position.

6. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke, means energizing said yoke in response to the flow of current through the breaker, an armature member adapted to be attracted to the yoke upon the occurrence of an overload current, a non-magnetic intermediate member positioned between the side legs of the yoke, a resilient metal strip mounted on said intermediate member and formed to provide a latching tip engaged by said releasable means, means interconnecting said intermediate member and said bimetallic member to provide for movement of the former upon flexing of the latter, and means providing for movement of said latching tip by said armature in its movement toward attracted position.

15 6. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke, means energizing said yoke in response to the flow of current through the breaker, an armature member adapted to be attracted to the yoke upon the occurrence of an overload current, a non-magnetic intermediate member positioned between the side legs of the yoke, a resilient metal strip mounted on said intermediate member and formed to provide a latching tip engaged by said releasable means, means interconnecting said intermediate member and said bimetallic member to provide for movement of the former upon flexing of the latter, and means providing for movement of said latching tip by said armature in its movement toward attracted position.

20 7. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke, means energizing said yoke in response to the flow of current through the breaker, an armature member adapted to be attracted to the yoke upon the occurrence of an overload current, a non-magnetic intermediate member positioned between the side legs of the yoke, a resilient metal strip mounted on said intermediate member and formed to provide a latching tip engaged by said releasable means, said strip being extended and engaging the bimetallic element with an abutment portion so as to be moved thereby upon flexing of the bimetal, said strip being disposed in the path of movement of the armature so as to be moved thereby upon its movement to attracted position.

J. G. JACKENSON.
